UNITED STATES PATENT OFFICE

CHARLES WILLIAM PRESSLEY, OF HOLLYWOOD, CALIFORNIA

PIANO

Application filed February 1, 1928. Serial No. 251,178.

This invention relates to certain improvements in pianos and a special object of the invention is to provide a piano having a foldable key-board and legs so as to require only about half the space now occupied by the average piano.

Another special object of the invention is to provide a piano having a larger sound board area.

Another special object of the invention is to provide a piano having a retractable music supporting device adapted to cooperate with the foldable key-board and therefore will be particularly adapted for use in any situation where economizing of space is important.

Another special object of the invention is to provide a piano with a complete box brace made of metal to hold the pin block in place; top, sides and bottom steadfast and provided with extra bracing in the back made in a lyre shape all of which is bolted through and through to the front.

Another special object of the invention is to provide an improved covering over a portion of the key-board so that dust and small objects used by musicians will be less apt to fall between the keys.

Another special object of the invention is to provide a piano having a metal strip at the top of the pin block in back so it will not yield forwardly.

Another special object of the invention is to provide a piano that will weight only about two hundred pounds when completed; a piano one man can handle, and where two can be shipped for the price of one, thus a conservation of space, weight and money.

The invention possesses other advantages and valuable features some of which with the foregoing will be set forth at length in the following description, wherein I shall outline in full the form of invention which I have selected for illustration in the drawing accompanying and forming a part of the present specification.

Although I shall describe the preferred form of my invention shown in the drawing and shall specifically mention certain of its more important objects, I do not wish to limit myself to the forms disclosed since various

changes and adaptations may be made therein without departing from the essence of my invention as hereinafter claimed; and objects and advantages other than those specifically mentioned, may be included within the scope of the claims.

In the accompanying drawings:

Fig. 1, is a perspective view of my improved piano showing it in open position.

Fig. 2, is a perspective view of my improved piano showing it in folded position.

Fig. 3, is a perspective view of my improved piano looking toward the back thereof and showing the case in folded position.

Fig. 4, is a section taken on the line 4—4 of Fig. 3.

Fig. 5, is an enlarged view of the upper portion of the aforesaid section.

Fig. 6, is a perspective view of a portion of the metal box brace and strap which supports the pin block frame.

The embodiment of the invention selected for the purposes of the present disclosure as best illustrating the improvements involved comprises a case 1, of substantially harp shape design having a foldable key-board 2, foldable legs 3, 3 of which Fig. 1 perspective shows the combination of parts in open position, while Fig. 2, shows the same in folded position.

The foldable legs 3, 3, each have a pivot joint 4, 4. The legs 3, 3 include horizontal top and bottom members 13, 13, and 14, 14 swingable therewith. Said legs also comprise the upright supporting pieces best shown in Fig. 1, which are interposed between the outer end portions of said horizontal pieces, where supports are most necessary.

The foldable key-board 2, includes a plurality of keys 5 and 21, is pivoted at its extremities by a pivot member 6, and when in folded position as illustrated in Fig. 2, assumes an upright position. In Fig. 2, pin members 9, 9 which engage slots 10, 10, of the foldable leg members, when the latter are in the extended position and the key-board is in the operative position, are prominently displayed and illustrate a preferred manner of interlocking the foldable key-board to the upper members 13, 13 of the legs 3, 3.

The foldable legs 3, 3 preferably swing in or they may be detached when desired.

In each of the aforesaid views comprising Figs. 1 and 2 other dominant features hereinbefore referred to are further designated by reference numerals of which 7 represents the adjustable curtain with its music support 8, 11 the roller cover and 12 the auxiliary sound board.

10 In Fig. 3 is illustrated a rear view disclosing the supporting framework. It comprises a continuous metal frame 26 of rectangular shape to which is fastened through the medium of the wood members 36 and 27, the sound board 29.

This construction is more readily understood by referring to Figs. 4 and 5 showing a section taken on the line 4—4 of Fig. 3.

Within the confines of the metal frame 26 20 is a metallic brace 37 of lyre effect which rigidly holds the metal frame 26 from distortion, as well as bracing the entire structure of the piano frame.

25 Interposed between the top and bottom members of the frame 26 are a plurality of vertical iron struts or braces 33 screwed thereto and they together with the metallic harp brace 37 and iron plate 26 are penetrated by a cross rod 31 which further establishes 30 the rigidity of the frame work. It also aids in producing a lyre effect as well as enhancing the attractiveness of that portion of the case. Just below the lower member of the frame 26 and fastened thereto is a wood timber 25 which runs the entire length of the piano. To this is joined the wooden side timbers comprising the vertical upright members.

35 Referring to Figs. 4, 5 and 6 the parts shown in section will now be described, the features constituting the invention being clearly brought out while those parts old and familiar in the art will be only cursorily alluded to.

40 The foldable key-board 2 in Fig. 4 is shown in both opened and closed position. On the extension of the middle balance rail 6^a of the key-board is the pivot pin 6. The member 24 having a felt covering 23 limits the downward movement of the keys 5.

45 The pin block 32 composed of hardwood is fastened to the metal frame 26 by an iron stirrup 34 having inwardly projecting flanges which are fastened to the metal frame 26 by 50 screws 35.

This stirrup, (see Fig. 6) keeps the pin block 32 from tilting forward when tension is put in the strings 30, by tightening the pins 28 into the pin block 32.

60 The curtain music support 7 is adjustable and is similarly constructed to an ordinary curtain, and comprises a roller 19 having a trunnion 18 at each end.

65 At the extremities of the roller 19 which runs the full length of the piano are provided

slots 19^a in the side members of the frame which hold the roller 19 in position.

The roller cover 11 having a pivotal axis 16 is similarly supported in a slot 16^a. Said cover also runs the full length of the piano 70 and is swingable upon its pivotal axis.

The pin block 32 is of variable height to form the harp effect and is covered with a metal plate 15 as shown in section illustrated in Figs. 4 and 5 and further illustrated in 75 Fig. 3.

The sounding board 29 which heretofore is the only means for amplifying the sound in pianos is augmented in my improved piano wherein I employ an auxiliary sound board 80 12 running the entire length of the piano.

Having thus outlined a preferred form of my invention, I claim:

1. In a device of the character described, a pivoted foldable keyboard unit, the under surface of which is finished and adapted for display when said keyboard unit is swung upon its pivotal axes from an extended to an upright position and foldable legs to support said key-board unit. 85

2. In a piano case simulating a harp, a foldable keyboard unit, a middle balance rail for the keyboard unit a pivotal support at each extremity of said balance rail and a finished surface adapted for exposure on the 95 under side of said key-board unit.

3. The combination, with a pair of leg members swingable through a horizontal plane from a retracted to an extended position; of a foldable key-board unit having a 100 finished under-surface and pivoted at its mid-width to swing about a horizontal axis from an extended to an upright position, a roller element mounted above said key-board unit when the latter is in upright position, and a 105 curtain carried by said roller adapted for vertical adjustment to accommodate itself to the variation in height of the key-board unit when in upright or extended position.

4. In a device of the character described, 110 a foldable key-board pivoted to swing about a horizontal axis from an extended to an upright position, in combination with a pair of leg members swingable through a horizontal plane from a retracted to an extended position, said leg members when extended being constructed and arranged to aid in supporting said key-board when the latter is extended, means to interlock said key-board with 115 said leg members when said key-board and leg members are in operative position, a roller element mounted above said key-board when the latter is in upright position, and a curtain carried by said roller adapted for vertical adjustment to accommodate itself to the 120 variation in height of the key-board when in upright or extended position.

5. In a device of the character described, a foldable key-board pivoted to swing about a horizontal axis from an extended to an up- 130

right position, in combination with a pair of leg members swingable through a horizontal plane from a retracted to an extended position, said leg members when extended being constructed and arranged to aid in supporting said key-board when the latter is extended, and a pin and socket arrangement to interlock said key-board with said leg member when said key-board and said leg members are in the operative position, said leg members each consisting of horizontal top and bottom pieces and an upright supporting piece disposed between the outer positions of said horizontal pieces.

15 6. In a device of the class described the combination with a key-board foldable from an extended to an upright position; of a roller element mounted above said key-board when the latter is in upright position, and a 20 curtain carried by said roller adapted for vertical adjustment to accommodate itself to the variation in height of the key-board when in upright or extended position.

7. In a device of the class described the 25 combination with a key-board foldable from an extended to an upright position; of a roller element mounted above said key-board when the latter is in upright position, and a curtain carried by said roller adapted for vertical 30 adjustment to accommodate itself to the variation in height of the key-board when in upright or extended position, and a shield for said roller covering the same and that portion of the curtain rolled thereon, said 35 shield being pivotally supported above said roller.

8. In a device of the class described the 40 combination with a key-board foldable from an extended to an upright position; of a roller element mounted above said key-board when the latter is in upright position, and a curtain carried by said roller adapted for vertical 45 adjustment to accommodate itself to the variation in height of the key-board when in upright or extended position, said curtain carrying an outwardly extended music support.

CHARLES WILLIAM PRESSLEY.
